[57] CLAIM

The ornamental design for a receptacle for syringes and other sharp articles with a trash compartment on top thereof, as shown and described.

DESCRIPTION

FIG. 1 is a perspective of the receptacle for syringes and other sharp articles with a trash compartment on top. The tray shown in broken lines in FIG. 1 is for illustrative purposes only.

FIG. 2 is a side view thereof taken from the left of FIG. 3.

FIG. 3 is a front view thereof.

FIG. 4 is a side view thereof taken from the right of FIG. 3.

FIG. 5 is a back view thereof.

FIG. 6 is a top view thereof.

FIG. 7 is a bottom view thereof.
